UNITED STATES PATENT OFFICE.

FRED W. BOCKSTEGE, OF EVANSVILLE, INDIANA.

DESIGN FOR A FOLDING TABLE.

Application filed November 21, 1922. Serial No. 4,353. Term of patent 3½ years.

To all whom it may concern:

Be it known that I, FRED W. BOCKSTEGE, a citizen of the United States, residing at Evansville, in the county of Vanderburg and State of Indiana, have invented a new, original, and ornamental Design for Folding Tables, of which the following is a specification, reference being had to the accompanying drawing, forming a part thereof,

which is a perspective view of a folding table showing my new design.

I claim:

The ornamental design for a folding table, as shown.

In testimony whereof I affix my signature.

FRED. W. BOCKSTEGE.
